HEAT EXCHANGER

John M. Gantvoort, Somerville, N. J., assignor to
 American Locomotive Company, New York,
 N. Y., a corporation of New York

Application September 25, 1945, Serial No. 618,555

5 Claims. (Cl. 257—245)

1

This invention relates to heat exchangers. An object of the present invention is to provide a heat exchanger having a shell partitioned by a row of thin plates into a row of narrow passages, and having inclined end walls of greater area than the cross-sectional area of the shell whereby adequate port areas and bolting rib areas may be provided.

A further object is to provide a header for each end wall of the aforesaid shell, the header having a greater cross-sectional area than the end wall.

Other and further objects of this invention will appear from the following description, the accompanying drawings and the appended claims.

Referring to the drawings forming a part of this application, Figure 1 is a foreshortened front view, on a reduced scale, of a heat exchanger constructed in accordance with this invention; Fig. 2 is a view of a portion of the exchanger; Fig. 3 is a fragmentary longitudinal vertical central section of the exchanger; Fig. 4 is a plan of the cast wall for each end of the exchanger; Fig. 5 is a plan of the cast header for each end of the exchanger; Fig. 6 is an end view, taken from the right, of the header of Fig. 5, parts of a nozzle flange being broken away; Fig. 7 is a section on the line VII—VII of Fig. 6; Fig. 8 is a section on the line VIII—VIII of Fig. 7, a nozzle being broken away; Fig. 9 is a section on the line IX—IX of Fig. 7; Fig. 10 is an enlarged section on the line X—X of Fig. 1, the corrugated element of each passage being indicated at the ends only thereof, in solid lines; Fig. 11 is an enlarged view of the front right corner of Fig. 10; Fig. 12 is a reduced view of a portion of an inner plate showing the solder winding thereof preparatory to fabrication of the exchanger; Fig. 13 is a view similar to Fig. 12 of an outer plate with solder bands thereon; and Fig. 14 is an end view of Fig. 13, taken from the left thereof.

A heat exchanger constructed in accordance with the present invention, and indicated generally by the reference numeral 1, is shown in horizontal position in the drawings and will be so described; it being understood that the exchanger may be disposed vertically if desired. While the invention is applicable to exchangers having two or more passages for two or more fluids, it is shown in connection with seven passages for three fluids.

The exchanger includes a shell 2, rectangular in cross section, having similar cast end walls 3, similar top and bottom walls 4 and similar

2

front and rear walls 5. Six spaced plates 6, parallel to walls 4, partition the shell into seven passages 7. Walls 4, plates 6 and passages 7 have their length horizontally. Plates 6 are considerably thinner than walls 4. The walls 3 are cast with seven slots 8; each disposed over one of the seven passages 7. The end edges 6a (Fig. 12) of plates 6 are formed with cut-out portions 6b at their lateral ends and are bent upwardly at 6c (Fig. 3) to extend into slots 8 and are permanently attached therein as by soldering. Similarly the top wall 4 is formed with cut-out portions 4a (Fig. 13) at its lateral ends and is bent outwardly at 4b (Fig. 3) to extend into the top slots 8 which are of substantially the same length as the bent portion 4b. Said top wall 4 is permanently attached to the wall 3 in the slot 8 as by soldering. The bottom wall 4 is fillet welded exteriorly to the inner faces of the walls 3.

The walls 5 are thinner than the walls 4 and are bent to provide outer longitudinal loops 9 and inner longitudinal loops 10, the loops opening inwardly of the shell. The longitudinal margins of walls 4 and plates 6 are permanently secured in loops 9 and 10 respectively, as by soldering, and the loops 9 are further strengthened by bolts 11 passing through orifices therein and in the enclosed margins of the walls 4. The end edges of the loops are welded exteriorly to the adjacent faces of walls 3.

Each passage 7 has disposed therein a corrugated element or membrane 12. Each element 12 is formed of a row of spaced U-shaped parts 13, each having two legs 14 perpendicular to the walls 4 and plates 6 and connected at one end by a U-bend 15. Adjacent legs 14 of adjacent parts are connected at their other ends by U-bends 16. The spaces between the legs run longitudinally of the shell.

Each of the U-bends is permanently attached, as by soldering, to the adjacent walls 4 or plates 6, as the case may be. The elements (membranes) extend the heat exchange surfaces of the walls 4 and plates 6 and furthermore, their legs provide tension members holding the walls 4 and plates 6 in rigid parallelism, preventing distortion thereof by pressures in the passages 7. The plates 6 tie the walls 5 together.

In order to solder the elements to the walls 4 and plates 6, the walls 4 have attached thereto during fabrication of the heat exchanger, rows of bands 17 of solder, each band 17 completely crossing the inner face of the wall 4 and being bent over the longitudinal edges of the wall, see Figs.

13 and 14. The plates 6 are similarly provided with bands by winding a continuous strip of solder 18 helically transversely around each plate, thus providing solder bands on opposite faces of the plate, as is clearly shown in Fig. 12. This solder attaches the elements to the walls 4 and plates 6 when the heat exchanger is put in a furnace and heated to a soldering temperature. The elements 12 are considerably thinner than the plates 6. The solder bands are also employed in securing the longitudinal edges of the walls 4 and plates 6 in the loops 9 and 10 respectively and in securing the end edges of the top wall 4 and of the plate 6 in the slots 8.

The features of the heat exchanger bearing on the side wall loops and the corrugated members form no part of the present invention except as they bear on the inclined end walls and headers of the present invention. For a further understanding of a heat exchanger having these features reference may be had to the application of Walter Gloyer and John M. Gantvoort, Serial No. 618,554, filed of even date herewith.

A header 19 is bolted to each of the walls 3. Each header, as shown in Fig. 7, has two large side compartments 20 and 21 and a center chamber or compartment 22. Nozzles 23, 24 and 25 open respectively into compartments 20, 21 and 22. The header has eight parallel walls 26 between compartments 20 and 21, forming seven chambers, each extending over a slot 8 in the wall 3, the center chamber being the chamber or compartment 22. This center chamber opens to the adjacent nozzle 25 and is otherwise closed by the adjacent walls 26 and end walls 27. Three of the remaining chambers, each indicated by the numeral 28, open into the compartment 20, and the remaining three chambers 29 open into the compartment 21.

Each of the passages 7 opens into oppositely disposed chambers and it will be noted that no adjacent passages 7 open to the same nozzle, the corresponding nozzles at opposite ends of the exchanger serving one as an inlet and the other as an outlet for the passage 7 or passages 7 communicating therewith. As aforesaid, the present heat exchanger is adapted for the passage of three fluids, one of the three fluids passing through the center passage 7 opening into compartments 22, another fluid passing through the passages 7 opening into the compartments 20 and the third fluid passing through the remaining passages 7 opening into the compartments 21.

Each wall 26 has bulges bored to provide bolt holes 30. Each end wall 27 of the center chamber or compartment 22 also has a bulge providing a bolt hole 30. The bulges extend completely through the header. Similarly, the closing end wall of each compartment 20-21 has a bulge providing a bolt hole 31 and three posts forming part of the casting extend through each compartment 20-21 and are bored to provide bolt holes 32. Holes 30 are perpendicular to the wall 3 when the header is superimposed thereon, but holes 31 and 32 are inclined. Wall 3 has a threaded bolt hole or recess 33 in line with each hole 30 so that the header can be firmly bolted to the wall 3 by bolts 34. There is a row of recesses 33 along each of the four margins of the wall 3 and a row of recesses 33 in each of the ribs between the slots 8. Wall 3 is of a size so that it extends only slightly beyond the chambers 22-28-29, leaving the compartments 20 and 21 laterally overhanging the shell. As is clearly shown in Fig. 1, the walls 3 and headers 19 are

disposed obliquely and the angle of the holes 31-32 is accordingly such that these holes are vertical when the shell is disposed horizontally. The holes 31-32 are employed in securing the exchanger to a mounting (not shown).

It is contemplated that the exchanger of the present invention will be of small cross-sectional size. For instance, the largest cross-sectional length of the shell, which is the cross-sectional length of the wall 4 as shown in Fig. 10, may be only eleven inches, Fig. 10 being substantially actual size. Accordingly, due to the thinness of the plates 6 and their closeness together, a problem of heading the passages 7 becomes apparent.

The present invention provides a header construction for the passages 7 which is simple, economical and which provides sufficient area for all the necessary parts despite the small cross-sectional area of the shell. That is, the area of the wall 3 is substantially larger than the cross-sectional area of the shell, due to the fact that the wall 3 is inclined. The slots 8 provide simple means for securing the thin plates 6 to the header. Furthermore, inclining the wall 3 provides sufficient metal (ribs) between the slots 8 to provide for the necessary large number of threaded recesses 33.

While there has been hereinbefore described an approved embodiment of this invention, it will be understood that many and various changes and modifications in form, arrangement of parts and details of construction thereof may be made without departing from the spirit of the invention, and that all such changes and modifications as fall within the scope of the appended claims are contemplated as a part of this invention.

The invention claimed and desired to be secured by Letters Patent is:

1. A heat exchanger comprising an open ended rectangular shell; a plurality of spaced parallel plate members in said shell extending longitudinally thereof and partitioning said shell into a plurality of individual narrow passages, said plate members being disposed between and parallel to two of the side walls of said shell and having a thickness substantially less than the thickness of said two side walls; a relatively thick closure plate secured to each of the opposite ends of said shell at an oblique angle thereto, each of said closure plates being provided with spaced ribs forming a plurality of parallel slots each in register with one of said narrow passages; and an open-faced header provided with a pair of oppositely disposed parallel nozzles and an intermediate nozzle secured on each of said closure plates, each of said closure plates and its correlated header forming a pair of oppositely disposed chambers and an intermediate chamber, said intermediate chamber being divided into a plurality of separate passages, including a central passage, in registration with the slots in said closure plate, each of said central passages communicating solely with the adjacent of said intermediate nozzles, the remaining separate passages of each of said intermediate chambers opening alternately in opposite directions into said oppositely disposed chambers adjacent thereto whereby separate fluid paths between each of the parallel nozzles of one header and its correlated nozzle of the opposite header are established independently of each other and the respective intermediate nozzles.
2. A heat exchanger as defined in claim 1 wherein the ribs are each of greater cross-sec-

tional width than the individual narrow passage with which it is in register.

3. A heat exchanger comprising a shell having a sloped open end; a plurality of plates partitioning the shell into passages; a closure wall secured to the sloped open end of the shell and disposed in a plane inclined to the planes of the plates, said wall having transmission slots opening one into each of the shell passages and dividing the wall into a plurality of ribs disposed one in line with each of the passages, the area of the face of each of said ribs being greater than the cross-sectional area of its correlated passage taken along a plane normal to all of the plates; a header secured to the wall provided with chambers and nozzles opening thereinto; means securing the headers to the ribs; and means at the opposite end of the shell to receive a plurality of fluids for transmission through the passages, slots, and header in heat-exchange relation.

4. A heat exchanger comprising a shell having a sloped open end; a plurality of plates partitioning the shell into passages; a closure wall secured to the sloped open end of the shell and disposed in a plane inclined to the planes of the partition plates, said wall having transmission slots opening one into each of the shell passages and dividing the wall into a plurality of ribs disposed one in line with each of the passages, the area of the face of each of said ribs being greater than the cross-sectional area of its correlated passage taken along a plane normal to all of the plates; a header having chambers therein separated from each other, one of said chambers being separately in communication with the middle transmission slot, another of said chambers being separately in communication with a slot adjacent said middle slot, another of said chambers being separately in communication with a slot adjacent said middle slot on the other side; a nozzle associated with each chamber; bolts securing the headers to the wall at the ribs; and means at the opposite end of the shell to receive a plurality of fluids for transmission through the passages, slots, and header to the nozzles in heat-exchange relation.

5. A heat exchanger comprising an open-ended shell having sloped end portions; a plurality of spaced parallel plates extending through the shell from end to end to partition the shell into a plurality of passages; a closure wall secured to each sloped end portion of the shell, each wall

having a plurality of parallel transmission slots each in communication with a shell passage and each dividing the walls into rib portions disposed one in line with each of the passages, the area of the face of each rib portion being greater than the cross-sectional area of the correlated passage taken along a plane normal to all of the partition plates; a header having walls therein in spaced parallel relation arranged to enclose the transmission slots, the middle pair of said walls having walls at their ends to form a chamber communicating with the middle transmission slot; a wall connecting said middle chamber wall to one end of the adjacent header wall to form an open-ended chamber in communication with a transmission slot adjacent the middle transmission slot; a wall connecting said middle chamber to the other end of the adjacent header wall on the other side of the middle chamber to form a chamber open at the end opposite the open end of the chamber adjacent the middle chamber on the first side, the last described chamber on said other side being in communication with the transmission slot adjacent the middle transmission slot on said other side; bolts securing the headers to the walls at the ribs; a plurality of nozzles associated with the header, each nozzle being in separate communication with one of said chambers; and means at the opposite end of the shell to receive a plurality of fluids for transmission through the passages, slots, and header to the nozzles in heat-exchange relation.

JOHN M. GANTVOORT.
